UNITED STATES PATENT OFFICE.

GUSTAV F. ANDERSON, OF BROOKLYN, NEW YORK, ASSIGNOR TO PARAGON CAN & CAP COMPANY, INC., OF PATERSON, NEW JERSEY, A CORPORATION OF NEW YORK.

RECEPTACLE CLOSURE.

Application filed May 28, 1923. Serial No. 641,839.

To all whom it may concern:

Be it known that I, GUSTAV F. ANDERSON, a subject of the King of Sweden, and a resident of the borough of Brooklyn, in the 5 county of Kings, city and State of New York, have invented certain new and useful Improved Receptacle Closures, of which the following is a specification.

This invention relates to closures for receptacles, such as bottles, having a depending flange or skirt to engage about the receptacle neck and secured to the receptacle by bending or crimping the edge portion of the flange below a shoulder on the receptacle. 10 To release the closure from the receptacle the closure skirt is arranged with an intermediate annular scoring to provide a weakened portion or line on which to disjoin or tear that portion from the closure skirt which engages the receptacle shoulder and retains it to the receptacle, said securing means also serving as a guard to prevent the surreptitious removal of the closure and tampering with or substituting the contents 15 in the receptacle, and then replacing the closure. This type of closure when once removed from the receptacle while it may be utilized as a dust cap for the receptacle it cannot be retained with a sufficient degree 20 of force to seal the opening of the receptacle with the result that the contents remaining in the receptacle deteriorate and become spoiled.

It is the object of the present invention 25 to provide a receptacle closure of this character in which after the rip or tearing strip of the closure has been torn or stripped from the closure to release it from the receptacle the closure skirt will be provided with portions adapted to yieldingly engage the shoulder 30 of the receptacle, and the closure may be removed from and replaced upon the receptacle by a slight pull or push and when applied to the receptacle in such manner make 35 a substantially air tight seal with the mouth of the receptacle, whereby a portion of the contents of the receptacle may be used and the remaining portion sealed within the receptacle without the liability of the remaining 40 contents becoming spoiled or deteriorating 45 due to it being open to the atmosphere.

In the drawing accompanying and forming 50 a part of the specification, Figure 1 is a side elevation of the neck portion of a receptacle with my improved closure applied

thereto, a portion of the closure being in section to show the arrangement thereof and the manner of securing the closure to the receptacle.

Figure 2 is a cross sectional view taken 60 on the line 2—2 of Figure 1 looking in the direction of the arrow.

Figure 3 is a perspective view of my improved closure looking at the lower end thereof; and

Figure 4 is a view similar to Figure 1 but with the tearing strip torn or disjoined from the closure and showing the manner of releasably retaining the closure on the receptacle after said strip is removed.

Similar characters of reference designate like parts throughout the different views of the drawing.

The embodiment of the invention shown in the drawing comprises a disk or top 5 to 75 engage at the opening of a receptacle R and having an annular depressed portion 6 to engage the edge of the mouth of the receptacle, with an interposed sealing material 7, such as a cork disk on a similar material, 80 and the disk 5 arranged with a depending flange or skirt 8 to engage about the neck of the receptacle. While the top and flange may be of integral structure stamped and drawn from a single piece of relatively ductile sheet metal, I preferably form the skirt or flange of a sheet of metal formed to tubular shape and secured together at the longitudinal edges with a seam, as at 9, similar to the forming of a can body, and then securing the disk 5 in one end by interlocking the peripheral portion thereof with the edge portion of the body, as at 10.

The receptacle R is arranged with an annular shoulder located a short distance from 95 the mouth of the receptacle which is preferably in the form of a bead 11 ordinarily arranged upon the neck of bottles. The flange or skirt of the closure is of a length to extend beyond said bead and the closure 100 is secured to the receptacle by applying pressure to the top to forcibly hold the top against the sealing material and the latter against the edge of the mouth and then crimping the edge portion of the flange below the shoulder or around the head, as by rolling or otherwise, to seal and secure the closure to the receptacle.

To release the closure from the receptacle the skirt is provided with a rip or tearing 110

- strip. For this purpose the so formed body or skirt is arranged with the usual hooks to form the interlocking seam 9 to extend to a point within the edge of the skirt or flange, as at 12, leaving a dividing cut or open portion from the seam to the edge of the skirt, one edge portion of which is notched or cut out, as at 13, while the other portion is formed as a tab or finger grip
- 14 adapted to lie in overlapped relation to the notched portion 13. To arrange the flange with the tearing strip it is intermediately and annularly scored on a zig zag or undulating line 15, this scoring line being arranged so that the portion 16 (Figure 4) of the flange will engage below the bead while the intermediate portion 17 will engage upon or be in line with the high portion of the bead. To release the closure the tab 14 is grasped by the fingers and by exerting a pull thereon the flange will be torn or disjoined on the zig zag line 15. To remove the closure from the receptacle, an axial pull is exerted thereon, and as the closure is made of relatively ductile material the extended portion 16 will spring outwardly and ride upon and over the body. Should it be desired to replace the closure all that is necessary is to push the closure upon the receptacle by a slight pressure of the hand, the portions 16 of the flange springing over and yieldingly engaging the receptacle bead not only holding the closure against accidental displacement but also maintaining a substantially air tight seal between the sealing material 7 and the mouth of the receptacle and thereby prevent deterioration and spoiling of the contents remaining in the receptacle.
40. By the arrangement of the seam 9 as described the tab is formed by a portion of the sheet which ordinarily constitutes a part of the seam, the tab being of a length equal to the portion of the sheet forming an interlocking hook of the same whereby there is a considerable saving of material which is a great desideratum in closures of this character considering the large quantities in which they are manufactured.
45. Having thus described my invention, I claim:
1. In a receptacle closure, a body to constitute the flange of the closure formed of a sheet rolled to tubular form connected at the longitudinal edges by a seam with part
- of the opposite edge portions adjacent an end of the body unseamed and said unseamed portions of the sheet adapted to overlap and arranged as a tearing strip by scoring the body circumferentially on a zig-zag line and an overlapped part of the unseamed portion serving as a finger tab for tearing the strip from the body, and a disk secured in one end of the body.
2. In combination a receptacle arranged with an annular shoulder and a closure therefor having a flange to extend beyond the receptacle shoulder when applied to the receptacle and adapted to be crimped below the shoulder, said closure flange having an annular zig-zag score to arrange the crimped portion as a tearing strip, and said scoring being arranged whereby portions of the closure flange will extend below the receptacle shoulder when the tearing strip is disjoined therefrom.
3. In combination a receptacle arranged with an annular shoulder, and a closure therefor having a flange to extend beyond the receptacle shoulder when applied to the receptacle and adapted to be crimped below the shoulder to secure the closure to the receptacle, said closure flange being weakened on a zig-zag line extending about the receptacle shoulder with a dividing cut extending from said weakened line through the edge of the closure flange to provide a tearing strip whereby as said strip is torn from the flange of a closure on a receptacle portions thereof will yieldingly engage below the receptacle shoulder and serve to retain the closure on the receptacle.
4. A receptacle closure comprising, a body, an element on the body adapted to be bent into sealing engagement with a portion of a receptacle, said element having a circumferential weakened line of zig-zag form therein, an end of said element below said line being available for seizure, whereby the part of said element below said line may be separated from the closure to permit manual removal of the closure from the receptacle while leaving said element provided with other parts adapted for reengagement with said portion of the receptacle to removably hold the closure thereon.
- Signed at Brooklyn, in the county of Kings, city and State of New York this 28th day of April, 1923.
- GUSTAV F. ANDERSON.
